PHONOGRAPH

Original application filed May 1, 1926, Serial No. 105,989. Divided and this application filed April 27, 1927. Serial No. 186,955.

This invention relates to improvements in sound recording and sound reproducing mechanism for phonographs, especially those used for recording and reproducing dictation.

This application is a division of my pending application, S. N. 105,989, filed May 1, 1926.

An object of this invention is to provide a simple, small and light-weight sound recording and reproducing mechanism which can be economically manufactured and easily assembled.

Another object of this invention is to provide a sound recording and reproducing mechanism in which most of the parts are formed of sheet metal, and are therefore easily manufactured.

This invention also provides an improved stylus mounting to improve sound recording and reproducing.

One embodiment of the invention herein-after referred to as a sound-box mechanism is here shown as applied to a dictation machine and is illustrated in the accompanying drawings, in which—

Figure 1 is a front elevation of the dictation machine, showing the aforementioned mechanism in position.

Fig. 2 is a top plan view of a sound-box mechanism, with the cover removed, taken on line 2—2 of Fig. 1.

Fig. 3 is a side plan view on line 3—3 of Fig. 1, and shows the mechanism in position for reproducing.

Fig. 4 is a side view partly in section taken on line 4—4 of Fig. 1, and shows the mechanism in position for recording.

Fig. 5 is a perspective view of the carriage frame made in accordance with the present invention.

As usual in dictation machines, the sound-box 62 illustrated herein is slidably and pivotally mounted in a carriage 25 which travels across the base or top plate 20 on guide rods 23 and 24 or the like. The carriage 25 is caused to travel by a feed-screw 98 engaging a feed-nut thereon so as to follow the sound grooves of a dictated record 33 or

to cut a helical groove in a blank record when recording.

In accordance with the present invention, the carriage 25 instead of being constituted by the usual intricate and complicated casting, consists merely of a sheet metal frame to provide an improved mounting for the sound-box 62. This frame has as its main parts a front wall 25a with integral side walls 25b which are bent rearwardly toward the usual record-supporting mandrel 31 as shown in Figs. 1 and 4 and serve to support parts of the mechanism and stiffen the structure so as to make it rigid. A sheet metal shelf 73 is located between the side walls 25b for slidably supporting a sleeve 70 for the sound-box and adds to the rigidity of the side-walls 25b and provides a maximum of support for the sound-box carrying sleeve 70 when this is in its most extended position.

In the present invention, sound is recorded on or reproduced from the record 33 supported by the mandrel 31 by a sound-box 62 mounted in the carriage 25, which is slidably mounted on the guide rods 23 and 24 carried by the standards 21 and 22.

The sound-box 62 comprises a sound-conveying tube 68 and an inverted pan 63, having the latter secured thereto by rubber gaskets and suitable adhesive such as bees-wax, a diaphragm 64 carrying the stylus-holder 65 in which there is mounted a recording stylus 66 and a reproducing stylus 67.

The pan 63 is secured to a supporting and sound-conveying tube 68 which is mounted in the carriage for free vertical movement so as to accommodate itself to records of different thicknesses and so as to rise and fall in following the irregularities and eccentricities of the record-surface. The pan 63 and tube 68 are also mounted for free lateral movement when reproducing, and have longitudinal movement for changing from sound-recording to sound-reproducing positions, the stylus 66 and 67 being set one in front of the other and being brought into position to engage the record by the said longitudinal movement of the pan.

For these purposes, the tube 68 of the sound-box 62 is mounted on horizontally dis-

posed trunnions 69 in a sleeve 70 which in turn is mounted on vertically disposed trunnions 69a mounted in a slide 71 and an arm 72 formed integral with the slide. The slide 71 rides on a shelf 73 in the carriage-frame 25 and is held and guided thereon by a pair of studs 74 threaded in the slide and having washers engaging the under-side of the shelf by the pressure of springs 75 located between the heads of the washers and the heads of the studs.

For controlling the slide with the sound-box which it supports, there is pivotally mounted on a hollow stud 76 on one wall of the carriage-frame 25, an arm 77 formed integral with a lever 78 extending through a slot 79 in the carriage-frame. This arm 77 passes through an aperture in the shelf 73 and engages the walls of the slot 80 in the slide. The arrangement is such that when the lever 78 is in its raised position as seen in Fig. 4, the arm 77 has moved the slide 71 rearwardly so that the recording stylus 66 is in engagement with the record-surface. When the lever 78 is lowered to its lowermost position, the arm 77 moves the slide forwardly and causes the reproducing stylus 67 to be located in record-engaging position.

In order that the styluses will not scratch the record surface when the pan 63 is shifted laterally and in order that the pan and the styluses may be held in inoperative position out of engagement with the record when the lever 78 is in an intermediate or neutral position, a sound-box controlling lever 81 having an arm 81a underlying the tube portion 68 of the sound-box is mounted on a pivot 82 on the slide 71 and this arm is provided with cam surface 83 adapted to engage a stationary abutment 84 mounted on the side wall of the carriage-frame. Hence, when the slide is moved in and out of the carriage-frame, the pan is raised from the record-surface, then moved longitudinally and then allowed to drop into record-engaging position as soon as the stylus to be used is in record-engaging position. Of course, when the lever 78 is in an intermediate position, the sound-box controlling lever 81 has the protruding portion of its cam in engagement with the abutment 84 and this holds the pan with the stylus off the record-surface.

While the lateral movement of the sound-box permitted by the trunnions 69a is desired and necessary for free tracking movement of the sound-box during sound-reproducing, it is undesirable to have this movement during recording, and hence the lower wall of the sleeve 70 is extended rearwardly and is provided with a longitudinal slot 85 clearly shown in Figures 2, 3 and 4 into which a holding pin 86 mounted in the shelf 73 extends when the sleeve 70 is moved rearwardly to bring the recording stylus into record-engaging position. When the pin 86 is lo-

cated in the slot 85 of the sleeve, no appreciable lateral movement of the sound-box is permitted, and consequently a true helical groove is inscribed on the record by the rotation of the mandrel and the traveling movements of the carriage.

In the operation of reproducing sound, it is desirable to have a certain amount of downward pressure on the pan or sound-box to hold the reproducing stylus against the surface of the record. This is provided by a weight 87 having arms 88 movable on the horizontal pivots 89 carried by the sleeve 70. However, it is not desirable to have this weight on the sound-box or pan during recording operation, for in such case the recording stylus would cut too deeply. To relieve the sound-box or pan of the pressure of the weight 87 during recording operation, the weight is provided with a rearwardly extending finger 90 adapted to move upwardly into and drop upon a support 91, formed integral with a cover 92 for the sound-box and sound-box carriage, when the sound-box is moved rearwardly to bring the recording stylus into engagement with the record.

It will be seen that the construction provided can be made and assembled economically, for the slide and the parts mounted thereon constitute a complete unit which can be placed upon the shelf 73 in the carriage and can be secured thereto by the two simple screw studs 74.

For the purpose of providing a coupling between the supporting and conveying tube 68 of the pan and a nozzle 93 on the carriage to which a speaking tube 94 may be secured, there is provided a coupling tube 95 located within an enlarged end 96 of the conveying tube 68 and flaring outwardly until it snugly fits the inside wall of the nozzle 93 on which it slides during the reciprocatory movements of the slide 71 and tube 68.

The sound-box carriage shown can also be economically manufactured, for it consists of a sheet metal stamped and formed to shape, so as to have a front wall and two side walls for supporting the mechanism which it contains.

The sound-box carriage also supports a feed-nut 97 which is adapted to engage a feed-screw 98 journaled in the standards 21 and 22 of the frame of the machine. The feed-nut 97 is mounted in a frame 99 pivoted at 100 in the side walls of the carriage and provided with a spring 101 for normally urging the feed-nut towards the feed-screw. In order to release the feed-nut when the control lever 78 is shifted to neutral position so that the carriage may be moved to position to start a new record or to any other position with respect of the record-surface, the control lever 78 is provided with a lug or arm 102 adapted to engage cam surfaces 103 on the nut-frame 99 during the shifting of the lever 104.

to neutral position in which position the lever is frictionally detained by a dwell 104 into which the lug extends, and in this position the feed-nut is held out of engagement with the feed-screw. The arrangement is such between the lug 102 and the cam surfaces 103 that the arm 77 engaging the slide 71 moves the slide sufficiently to cause both styluses to be off the record-surface before the feed-nut is withdrawn from engagement with the feed-screw. This arrangement prevents the carriage from being moved laterally by hand while either stylus is in engagement with the record surface.

15 It will be noted that the feed-nut 97 instead of being merely mounted on an arm is mounted on a broad plate or frame and this is done so that the plate will protect the feed-nut and feed-screw from dust or the shavings 20 from the record and so as to close the back of the sound-box carriage 25 against tampering by curious persons.

It will be noted that the feed-nut frame 99 performs three functions—(1) to carry 25 the feed-nut into and out of engagement with the feed-screw; (2) to keep the feed-screw and feed-nut clean; and (3) to serve as a detent for holding the control lever in neutral position.

30 The control lever is held in reproducing and recording positions against accidental movement by a spring detent 105 engaging dwells or notches 106 in an arcuate extension of the arm 102 on the control lever.

35 The simple operation of moving the lever 78 from recording to reproducing position causes the last few lines of recording to be reproduced without moving the carriage 25 backwardly. This is accomplished by off- 40 setting the reproducing stylus 67 longitudinally of the machine with respect of the recording stylus 66 and the extent of offset is sufficient to just reproduce the last portion of the matter recorded. Conversely, when the 45 matter recorded has been reproduced and the operator desires to again record, the movement of the control lever 78 to recording position causes the recording stylus to engage the record in advance of the last groove recorded.

50 Hence, there is no danger of the recording stylus re-engaging a groove which is already recorded and obliterating the matter recorded.

Variations and modifications may be made 55 within the scope of this invention and portions of the improvements may be used without others.

Having now described the invention, what is claimed as new and for which it is desired 60 to obtain Letters-Patent, is:—

1. In a phonograph, in combination, a frame, a record-support rotatably mounted on said frame, a sound-box, a carriage for the sound-box mounted on said frame and comprising a sheet metal member having only

side walls and a connecting front wall, and means between the walls of said member for slidably mounting the sound-box.

2. In a phonograph, the combination of a frame; a record-support rotatably mounted on said frame; a sound-box; a carriage for the sound-box mounted on said frame and comprising a sheet-metal member having a front wall and also having side-walls integral with the front wall and extending rearwardly toward the record-support; and a sheet-metal shelf located between said side-walls and adapted to slidably support the sound-box.

3. In a phonograph, in combination, a frame, a record-support rotatably mounted on said frame, a sound-box, a carriage for the sound-box mounted on said frame and comprising a sheet metal member having only side walls and a connecting front wall, means between the walls of said member for slidably mounting the sound-box, and a second sheet metal member secured to said first sheet metal member and forming a protective cover for said sound-box.

4. In a phonograph, the combination of a frame; a record-support rotatably mounted on said frame; a sound-box; a traveling sheet-metal member for supporting said sound-box mounted on the frame, said member having a front-wall and also having side-walls integral with the front wall and extending rearwardly toward the record-support; a sheet-metal shelf mounted between the side-walls; a slide mounted on said shelf; and means on the slide for carrying the sound-box.

5. In a phonograph, in combination, a frame, a record-support rotatably mounted on said frame, a sound-box, a traveling carriage for the sound-box mounted on the frame and comprising a member open at its rear end toward the record-support and having a front wall and a pair of rearwardly extending side walls, feed mechanism for the carriage comprising a feed-screw and a feed-nut, and a plate on which the feed-nut is supported, said plate being pivotally mounted between said side walls of said member and adjacent the rear edges thereof, whereby said plate serves as a closure for the rear end of said carriage member.

6. In a phonograph, the combination of a frame; a record-support rotatably mounted on said frame; a sound-box; a traveling carriage for the sound-box mounted on the frame and comprising a member open on the side adjacent the record-support; feed-mechanism for the carriage comprising a feed-screw and a feed-nut; and a plate carried by the carriage on which the feed-nut is mounted, said plate being located between the record-support and the feed-screw, and the nut being located on the plate at a point remote from the record-support whereby shavings

from a record-support carried by the record are prevented from falling upon the feed-nut.

7. In a phonograph, the combination with a frame, a record-support mounted on said frame, a sound-box, a tone-tube supporting said sound-box, a carriage movably mounted on said frame, a slide mounted on said carriage for sliding movement transversely of said record-support, said tone-tube being pivotally mounted on said slide, and a lever pivoted on said slide and having a portion underlying said tone-tube for raising said tone-tube and sound-box away from said record-support at certain points in the path of movement of said slide.

8. In a phonograph, the combination of a frame, a record-support mounted longitudinally thereof, a sound-box, a tone-tube supporting said sound-box, a carriage movably mounted longitudinally of said frame, means for mounting said tone-tube on the carriage for sliding movement transversely of said record-support, a lever pivoted on said mounting means having a portion underlying said tone-tube, and means positioned on the carriage adapted at certain points in the path of movement of said mounting means to lift said lever and cause said sound-box to assume inoperative positions relative to said record-support.

9. In a phonograph, in combination, a frame, a record-support mounted thereon, a sound-box, a carriage for the sound-box mounted on the frame and comprising a sheet metal member consisting solely of a front wall and integral side walls which extend rearwardly toward the record-support, and a cover for the carriage adapted to overlap and engage the front wall and embrace the side walls of said member to prevent said side walls from being sprung apart.

Signed at Bridgeport, in the county of Fairfield, and State of Connecticut, this 26th day of April 1927.

CERTIFICATE OF CORRECTION.

Patent No. 1,876,273.

September 6, 1932.

ALFRED V. BODINE.

It is hereby certified that error appears in the printed specification of the above numbered patent requiring correction as follows: Page 1, line 79, strike out the words "the latter" and insert the same before "having" in line 78; page 4, line 1, claim 6, for the compound word "record-support" read record, and same line, for "record" read record-support; and line 41, claim 9, for "members" read member; and that the said Letters Patent should be read with these corrections therein that the same may conform to the record of the case in the Patent Office.

Signed and sealed this 22nd day of November, A. D. 1932.

**M. J. Moore,
Acting Commissioner of Patents.**
